UNITED STATES PATENT OFFICE.

AUGUST RIEBE, OF BERLIN, GERMANY.

BALL-BEARING.

No. 824,820.

Specification of Letters Patent.

Patented July 3, 1906.

Application filed November 6, 1905. Serial No. 286,026.

To all whom it may concern:

Be it known that I, AUGUST RIEBE, engineer, a subject of the King of Prussia, German Emperor, residing in Berlin, N. W., 5 Hüttenstrasse 34-35, in the Kingdom of Prussia, Germany, have invented certain new and useful Improvements in or Connected with Partition Devices for Ball-Bearings, of which which the following is a full, clear, and exact 10 description.

The spring-acting intermediate pieces between the balls which have come into such general use in connection with ball-bearings have often excessive demands made upon 15 them in consequence of the accelerative power imparted to the balls and the compression together of the latter thereby caused, the result of which is the increased wear and tear and ultimate destruction of the springs, as 20 well as of the end plates, which in the case of the partition device selected as an illustration of the present invention form a closure for the springs at both ends, thus imperiling the precise action of the bearing. In order 25 to overcome this evil and for the purpose of regulating the admissible compressibility of the spring insertions or partition devices, a laterally-expansile sleeve *d* is, according to 30 the present invention, fitted onto, so as to more or less embrace, the springs of the said insertions, the sleeve in question being open laterally with a spring action in a tangential direction and stiff in an axial direction, whereby compression, beyond a certain point, 35 of the spring parts of the partition devices brought into action can be avoided. For instance, in the device selected for illustration the balls, even when the partition device is fully compressed, are able to issue from their 40 recesses in the end plates. In the latter case the compressibility of the spring-acting partition device—that is, the length of sleeve *d*—must be so regulated that the play allowed for spring action shall be less than the depth 45 of the recesses *e* in the end plates *b*, because if the play should exceed the depth of the recesses *e* in the end plates the balls would, in the case of an overcompressed intermediate piece, of themselves come out of their respective recesses, and so considerably interfere 50 with the working.

In the accompanying drawings the invention is illustrated, by way of example, in conjunction with a known spring-acting partition device or intermediate piece consisting of the two end plates *b* and the spring *c*.

Figure 1 is a longitudinal section showing one of the end plates in elevation. Fig. 2 is a cross-section on the line 2 2 in Fig. 1. Fig. 3 is an end elevation of another style of sleeve. 60 Fig. 4 is a cross-section showing a third style of sleeve. Fig. 5 is a side elevation with the rings partly broken away, illustrating the parts assembled in a bearing.

The device shown in Fig. 3 is designed for 65 cases in which special constructional conditions require the spring *c* to be completely enveloped by the expansile sleeve *d*. In such cases the latter must, as shown, be made in two parts *d'* and *d''*, overlapping each other 70 and supporting over their entire end surfaces the two end plates *b* when the spring-acting partition devices are in a compressed position.

In the example given at Fig. 4 is illustrated a modification of the device hereinbefore 75 described. As hereinbefore mentioned, the sleeve *d* must in order to be pressed over the spiral spring *c* have an opening or slit of a size approximating the diameter of said spring; but, owing to this notch or slit, in 80 cases where only one sleeve *d* is used there is no continuous support for the end plates. In fact, the plates are deprived of support in the part where the slit or opening comes, so that in certain positions of the device the end 85 plates are, owing to this lack of support and owing to the one-sided ball-pressure, liable to tip or tilt longitudinally of the device, the transverse line *x y* connecting the outermost 90 opposite corners of the sleeve *d* forming the 95 tilting or tipping axis. This risk of tipping is of course increased by the point of contact of the ball not being in the center of the end plate, but situated eccentrically with relation to the same.

When the position of the partition device is such that the point of contact of the ball reaches its nearest position to the tilting axis, this point of contact may under given conditions be so close to the tipping or tilting edge 100 that the sleeve *d* is not able at this point to give any support to the end plates, whereby the utility of the sleeve *d* itself is also rendered quite illusory. In order to overcome this difficulty, it has been found that the best 105 construction for the sleeves is that illustrated in Fig. 4, in which the sleeve *d*, in contrast to the previous form of construction, is extended at its two edges beyond the tipping or tilting line *x y* in such a way as to form two extensions *d'*, which do not in any way interfere with the placing of the sleeve over the spi-

ral spring e , but entirely prevent the tipping or tilting of the end plates under the conditions described above. It is obvious that with this form of construction there can be no tipping or tilting of the end plates even if the point of contact of the ball approaches unduly the tipping-line $x y$, as the vertical extensions d^o then provide the necessary support.

10. What I claim as my invention, and desire to secure by Letters Patent, is—

1. In compressible partition devices for ball-bearings, means for limiting the compression sufficiently to prevent the removal of such devices, said means being attachable to and detachable from the device.
2. In partition devices for ball-bearings, the combination with a spring and end plates, of a sleeve adapted to be introduced and

withdrawn laterally over said spring, the 20 length of said sleeve being such as to limit the movement of the end plates toward each other so as to prevent such compression as would permit the device from escaping from between the rings.

3. In partition devices for ball-bearings a spring, a pair of end plates, and a sleeve d adapted to be introduced laterally over the spring and having extensions d^o to provide bearings for the end plates beyond the opening in the sleeve.

In witness whereof I have hereunto signed my name in the presence of two subscribing witnesses.

AUGUST RIEBE.
